IGNITER

Robert Reddy, Pasadena, Calif., assignor to the United States of America as represented by the Secretary of the Air Force

Application July 3, 1956, Serial No. 595,800

6 Claims. (Cl. 60—39.82)

This invention relates to an igniter for a combustion apparatus and, more particularly, to a multistage igniter primarily for use with hypergolic propellants.

Combustion chambers of rocket engines, for example, require a flame having high heat intensity for igniting the fuel propellant. If a flame of the required high intensity were produced rapidly in the igniter, there would be danger of an explosion in the igniter. If an attempt were made to create such a large flame suddenly in the combustion chamber, there also exists the possibility that the fuel in the combustion chamber would not ignite and an expensive procedure would result in ultimately igniting the fuel by creating a flame of high heat intensity in the combustion chamber. The igniter of the present invention creates the desired flame of sufficient intensity by igniting the propellants gradually rather than rapidly.

An object of the present invention is to provide an igniter that produces a substantial ignition flame therein at a gradual rate.

Another object of this invention is to provide an igniter that projects its flame into a combustion chamber when the flame has a sufficient intensity to ignite the fuel in the combustion chamber.

Other objects will be readily perceived from the following description.

This invention relates to an igniter having two ignition chambers in communication with each other. Fuel is initially supplied to the smaller of the two ignition chambers by suitable means for ignition therein. As the pressure resulting from the combustion in the smaller chamber is transmitted to the larger ignition chamber, fuel is supplied to the larger chamber by suitable means in response to this pressure increase in the second chamber. This fuel, of course, is ignited in the larger chamber.

The attached drawings illustrate preferred embodiments of the invention, in which

Fig. 1 is a side elevational view of the igniter of the present invention;

Fig. 2 is a sectional view taken along the line 2—2 of Fig. 1; and

Fig. 3 is a sectional view showing a modification of the igniter of Figs. 1 and 2.

Referring to the drawings and particularly to Figs. 1 and 2, there is shown an igniter housing 10 including a primary ignition chamber 11 and a secondary ignition chamber 12 in communication with each other. A fuel, such as a hypergolic propellant, is supplied to the primary ignition chamber 11 through a tube 14. The fuel propellant is preferably JP-3 aviation fuel but other suitable hypergolic fuel propellants may be employed, if desired. It is only necessary that the fuel be noncombustible until it is mixed with an oxidizer at which time it becomes combustible. A tube 15 supplies an oxidizer propellant, preferably white fuming nitric acid, to the primary ignition chamber 11. The tubes 14 and 15 are wrapped around an electrical heating element 16 so that both the fuel and the oxidizer propellants are heated before delivery to the primary ignition chamber 11. The heating element 16 has

2

wires 17 and 18 connected to a suitable source of electrical power (not shown). The electrical heating element 16 and the tubes 14 and 15 are insulated by suitable insulating material 19 to permit maximum transfer of heat from the element 16 to the tubes 14 and 15.

The housing 10 includes a pair of cylinders 20 and 21 having pistons 22 and 23 movable therein, respectively. A nozzle 24 is disposed on the end of the piston 22, which is shown in cross section in Fig. 2. It will be understood that the movement of the parts of the piston 22 and the cylinder 20 also applies to the cylinder 21 and the piston 23, which are not shown in cross section. A passage 25 extends through the center of the piston 22 and a plurality of radially extending passages 26 is in connection with the passage 25. As is readily seen, the radial passages 26 are spaced along the passage 25.

As the pressure in the primary ignition chamber 11 increases due to the combustion therein, the pressure is transmitted into the secondary ignition chamber 12 and against the faces of the pistons 22 and 23, which are in communication with the secondary ignition chamber 12. This pressure increase results in the piston 22 moving against the force of a spring 27, which is disposed between the cylinder 20 and the piston 22. As the piston 22 moves outwardly against the force of the spring 27, the outermost of the passages 26 communicates with an annular port or groove 28 in the wall of the cylinder 20. The annular port 28 is supplied with the fuel propellant through a tube 29 that is connected to the fuel source (not shown). It will be understood that an annular port in the wall of the cylinder 21 is connected to an oxidizer source (not shown). As the outermost of the passages 26 communicates with the annular port 28, the fuel passes therethrough into the passage 25 and through the nozzle 24 into the secondary ignition chamber 12. Similarly, the oxidizer passes through the outermost of the radial passages in piston 23 and through the central passage and nozzle into the secondary ignition chamber 12. It will be understood that the size of the radial passages in the piston 23 is in proportion to the size of the radial passages 26 in the piston 22 in the same ratio as desired between the mixture of oxidizer and fuel to produce combustion. This mixture ratio, of course, depends on the oxidizer and the fuel employed.

The heat generated in the primary ignition chamber 11 is transmitted into the secondary chamber 12 where the fuel entering the secondary chamber 12 through the nozzle 24 is ignited. This, of course, further increases the pressure exerted against the face of the piston 22 to move the piston 22 further outwardly whereby more of the passages 26 communicate with the annular port 28 to increase the supply of fuel through the nozzle 24 to the secondary ignition chamber 12. It will be understood that the piston 23 is likewise exposed to the pressure from the chamber 12 and supplies the desired proportional quantity of the oxidizer through its nozzle (not shown).

The housing 10 has a passage 30, which connects the secondary ignition chamber 12 with a combustion chamber 31 of a rocket engine, for example. A poppet valve 32 controls the passage 30 to prevent communication between the secondary ignition chamber 12 and the combustion chamber 31 until a predetermined pressure exists within the secondary ignition chamber 12. The existence of this predetermined pressure within the secondary ignition chamber 12 indicates a flame has been created sufficient to ignite the propellants in the combustion chamber 31. The poppet valve 32 is held in its closed position by a spring 33 acting against a flanged member 34, which is secured to one end of a rod 35 on the other end of which the poppet valve 32 is formed. The amount of force required to open the poppet valve 32 depends on the force of the spring 33.

Considering the operation of the embodiment of the present invention shown in Figs. 1 and 2, the fuel is supplied through the tube 14 and the oxidizer through the tube 15 to the primary ignition chamber 11 for combustion therein. The heating element 16 heats both propellants prior to their delivery into the primary ignition chamber 11. Since the quantity is small and the propellants are heated, the propellants easily ignite hypergolically. As the primary ignition chamber 11 communicates with both the secondary ignition chamber 12 and the pistons 22 and 23, the pressure created by the combustion in the primary chamber 11 is transmitted to the secondary chamber 12 and the pistons 22 and 23. As this pressure increases, the pistons 22 and 23 are forced outwardly in their respective cylinders 20 and 21 to allow communication between the annular port and at least one of the radial passages. This supplies the fuel and oxidizer propellants to the secondary chamber 12 where they are ignited readily as they enter the secondary ignition chamber 12 due to the heat therein.

The additional combustion in the secondary ignition chamber 12 creates additional pressure whereby the pistons 22 and 23 move to the full extent of their travel and permit communication between the annular groove and all of the radial passages to supply a larger amount of the propellants through the nozzles to the secondary ignition chamber 12. The increasing combustion resulting from the larger supply of propellants to the secondary ignition chamber 12 causes a further pressure increase in the secondary ignition chamber; this further pressure increase in the secondary ignition chamber moves the poppet valve 32 against the force of the spring 33 to open the passage 30 and the flame emerges from the igniter housing 10 into the combustion chamber 31 of the rocket engine to ignite the propellants therein. It will be understood that the flow of propellants to the igniter is stopped upon ignition within the combustion chamber 31 of the rocket engine; this reduces the pressure in the secondary ignition chamber 12 and the spring 33 automatically moves the poppet valve 32 to close the passage 30 and prepare the igniter for a new cycle.

A modification of the embodiment of Figs. 1 and 2 is shown in Fig. 3 where both propellants are supplied to the secondary ignition chamber through a single piston and cylinder rather than through separate pistons and cylinders. The igniter housing 10' has both a primary ignition chamber 11' and a secondary ignition chamber 12' communicating with each other. A tube 14' supplies a fuel propellant to the primary ignition chamber 11' while a tube 15' supplies an oxidizer propellant to the primary ignition chamber 11'. Both of these tubes are wrapped around an electrical heating element 16', which is disposed within the igniter housing 10' to heat the propellants prior to their delivery to the primary ignition chamber 11'. The heating element 16' has wires 17' and 18' connected to a suitable source of electric power (not shown). The heating element 16' and the tubes 14' and 15' are insulated by suitable insulating material 19' to produce the maximum effective heat transfer between the heating element 16' and the tubes 14' and 15'.

The housing 10' includes a cylinder 40 having an annular piston 41 movable therein in response to pressure in the secondary ignition chamber 12'. The cylinder 40 has an outer annular passage 42 extending therethrough and connected to a fuel propellant source (not shown). An inner annular passage 45, which is connected to an oxidizer source (not shown), also extends through the cylinder 40. A plurality of slanting passages 43 connects the passage 42 and a plurality of slanting passages 46 connects the passage 45 with the annular portion of the cylinder 40 in which the annular piston 41 moves. A spring 44, which is disposed between the wall of the cylinder 40 and the piston 41, urges the piston 41 to the position shown in Fig. 3 where the passages 43 and

46 are closed by the piston 41. As the pressure in the secondary ignition chamber 12' increases due to the ignition of the propellants in the primary chamber 11', the pressure forces the piston 41 against the spring 44 to open some of the passages 43. This permits fuel propellant to flow through the passage 42 and the passages 43 and oxidizer propellant to flow through the passage 45 and the passages 46 into the secondary ignition chamber 12' where they are ignited by the heat resulting from the initial combustion in the primary ignition chamber 11'. This creates a pressure increase in the secondary ignition chamber that finally results in all of the passages 43 and 46 being opened to further increase the supply of fuel and oxidizer propellants to the secondary chamber 12'. This additional pressure increase in the chamber 12' acts against the poppet valve 32' to overcome the force of the spring 33' to open the passage 30' and allow the flame, which was created in the secondary ignition chamber 12', to enter the combustion chamber 31'. It will be noted that the passages 43 and 46 are slanted to direct the propellants in a jet type manner into the secondary chamber 12'. The size of the passages 46 is proportioned with respect to the size of the passages 43 in the same ratio as the desired mixture of oxidizer to fuel required to produce combustion.

Thus, the operation of the modification of Fig. 3 is substantially the same as that described with respect to Figs. 1 and 2 with the difference being that a single piston and cylinder are employed to supply both propellants to the secondary ignition chamber rather than two cylinders and pistons. It also will be noted that the nozzles of the modification of Figs. 1 and 2 have been eliminated by the slanting passages 43 and 46.

While the description refers to the employment of a fuel propellant and an oxidizer propellant being heated to produce the ignition, it will be understood that a spark could be relied upon to ignite the fuel in the primary ignition chamber and a spark also could be used in the secondary chamber if the fuel employed were not of the type ignited from the heat caused by the ignition in the primary chamber. The only requirement is that some type of means be employed for creating a gradual rate of ignition of the fuel in the igniter housing and the flame not be released therefrom until it has sufficient intensity to ignite the fuel within the combustion chamber to which the igniter housing is connected.

An advantage of the present invention is that it prevents an explosion in the combustion chamber until a satisfactory flame is available for igniting the fuel therein. A further advantage of this invention is that it creates a substantial flame but ignites the fuel gradually rather than rapidly. Still another advantage of this invention is that it is less expensive for starting combustion in a combustion chamber since less fuel is wasted if there is a failure in the igniter housing of the present invention rather than in a device having the starter ignition in the combustion chamber per se.

For purposes of exemplification, particular embodiments of the invention have been shown and described according to the best present understanding thereof. However, it will be apparent that changes and modifications in the arrangement and construction of the parts thereof may be resorted to without departing from the true spirit and scope of the invention.

I claim:

1. In combination, a combustion chamber, an igniter for the combustion chamber including a first ignition chamber and a second ignition chamber in communication with each other, means to admit fuel to the first ignition chamber, means to ignite the fuel in the first ignition chamber, means to supply fuel to the second ignition chamber in response to a pressure increase in the second ignition chamber for ignition in the second chamber comprising integrally formed fuel and oxidizer passage means and integrally grooved piston means hav-

ing a forward set of proportionally related, radially extending grooves in communication between said fuel and oxidizer passage means and said second chamber to form a combustible mixture therein acted on by the heat generated in said first chamber and a plurality of rearward, radially extending grooves integrally formed in said piston means to progressively increase the supply of combustible mixture formed in said second chamber on movement of said piston means in accordance with the increase of pressure of the combustion in said first chamber, and means responsive to a further pressure increase in the second chamber to direct the flame in the second chamber to the combustion chamber.

2. An igniter including a first ignition chamber, a second ignition chamber in communication with the first ignition chamber, means to admit fuel to the first ignition chamber, means to ignite the fuel in the first ignition chamber, and piston means normally spring urged to closed position movable in response to a pressure increase in the second ignition chamber to a progressively open position to initially supply a minimum of fuel and oxidizer to the second ignition chamber for ignition in the second chamber and having radially extending conduits formed therein in progressive communication with said second chamber to progressively increase the mixture of fuel and oxidizer therein in accordance with the increase of pressure in said first chamber.

3. In combination, a combustion chamber, an igniter for the combustion chamber including a first ignition chamber and a second ignition chamber in communication with each other, means to admit fuel to the first ignition chamber, means to ignite the fuel in the first ignition chamber, piston means movable in response to a pressure increase in the second ignition chamber to supply fuel to the second ignition chamber for ignition therein, said piston means increasing the supply of fuel as the pressure in the second ignition chamber increases, a passage connecting the second ignition chamber with the combustion chamber, and valve means to control the passage, said valve means being responsive to a predetermined pressure in the second ignition chamber to open the passage to allow the flame to enter the combustion chamber, said piston means comprising a cylinder positioned adjacent one end of said second ignition chamber, an annular piston mounted within said cylinder normally urged to its closed position with one face thereof in open communication with the interior of said second ignition chamber, an outer fuel supply conduit and an inner oxidizer supply conduit incorporated in said cylinder, and a plurality of fuel-oxidizer conduits integrally formed in said piston in progressive open communication with said fuel and oxidizer supply conduits on progressive movement of said piston by a predetermined pressure within said second ignition chamber.

4. In combination, a combustion chamber, an igniter for the combustion chamber including a first ignition chamber and a second ignition chamber in communication with each other, means to admit fuel to the first ignition chamber, means to ignite the fuel in the first ignition chamber, means to supply fuel to the second ignition chamber for ignition therein, means to control the supply means in accordance with the pressure in the second ignition chamber whereby a pressure increase in the second ignition chamber increases the supply of fuel thereto comprising at least one resiliently mounted, annularly disposed piston normally held in closed position with one face thereof communicating with the interior of said second ignition chamber and acted on by a predetermined pressure therein to move to open position, said piston having fluid passages in communication with said supply means to transfer fuel into said second ignition chamber when said piston is moved to open position, a passage connecting the sec- 75

ond ignition chamber with the combustion chamber, and poppet valve means to control the passage including an elongated valve member integrally formed on said valve means and having spring urged means on the other end thereof normally resisting the pressure within said second ignition chamber until the flame formed therein effects a further pressure increase above a preset minimum, said valve means being responsive to a predetermined pressure in the second ignition chamber to open the passage to allow the flame to enter the combustion chamber.

5. An igniter including a main housing having a first ignition chamber, a second ignition chamber in communication with the first ignition chamber, means to admit fuel to the first ignition chamber, means to supply fuel to the second ignition chamber for ignition therein, and means to control the supply means in accordance with the pressure in the second ignition chamber where- 15 by a pressure increase in the second ignition chamber increases the supply of fuel thereto comprising a cylinder incorporated within said main housing adjacent to said second ignition chamber having an outer annular passage extending therethrough and adaptable for connection to a source of fuel propellant and an inner annular passage extending therethrough and adaptable for connection to a source of oxidizer and having a plurality of fluid passages, respectively, connecting said outer and inner annular passages with an annular portion of said cylinder interiorly thereof, and an annular piston movably mounted within said annular portion adjacent to one end of said plurality of fluid passages normally closing said passages in one position thereof and gradually movable under a predetermined pressure 20 within said second ignition chamber to a second, open position to progressively open said fluid passages and effect increasing flow of fuel and oxidizer therethrough into said second ignition chamber in accordance with the pressure increase within said second chamber.

6. An igniter including a first ignition chamber, a second ignition chamber in communication with the first ignition chamber, means to admit fuel to the first ignition chamber, piston means having nozzle means in communication with said second ignition chamber and having a plurality of spaced grooves movable therewith in response to a pressure increase in the second ignition chamber to open communication between a supply of fuel and oxidizer and said second ignition 25 chamber for ignition in the second chamber, said piston means progressively increasing the number of grooves formed therein in communication between the supply of fuel and oxidizer in said second chamber to increase the supply of fuel and oxidizer delivered thereto as the pressure in the first ignition chamber increases, a passage connecting the second ignition chamber with a main combustion chamber or the like, and valve means to control the flow of flame through the passage, said valve means being movable to its open position only 30 on response to a pressure above a predetermined pressure in the second chamber to open the passage to allow a flame of sufficient heat intensity to enter the combustion chamber.
